CLAIM

The ornamental design for a smart watch, substantially as shown and described.

DESCRIPTION

FIG. 1 is a front and right side perspective view of a smart watch showing the new design;

FIG. 2 is a rear and right side perspective view of the smart watch of FIG. 1;

FIG. 3 is a front elevational view of the smart watch of FIG. 1;

FIG. 4 is a rear elevational view of the smart watch of FIG. 1;

FIG. 5 is a left side elevational view of the smart watch of FIG. 1;

FIG. 6 is a right side elevational view of the smart watch of FIG. 1;

FIG. 7 is a top plan view of the smart watch of FIG. 1;

FIG. 8 is a bottom plan view of the smart watch of FIG. 1;

FIG. 9 is a partial enlarged view of the smart watch of FIG. 1; and,

FIG. 10 is a partial enlarged view of the smart watch of FIG. 4.

The broken lines shown in the drawings represent portions of the smart watch that form no part of the claimed design. The dot-dash broken lines encircling portions of the smart watch in FIGS. 1 and 4 and illustrated in enlarged views in FIGS. 9 and 10 form no part of the claimed design.

1 Claim, 10 Drawing Sheets
